VARIABLE INDUCTANCE

Paul Ware, New York, N. Y.

Application July 17, 1935, Serial No. 31,823

5 Claims. (Cl. 171—242)

This invention relates particularly to radio receivers and is specially applicable to so-called all-wave sets, although various features of the invention may have other applications.

5 The tuning of a resonant radio circuit is usually accomplished by varying the capacity associated with a fixed inductance. With a given variable capacity, different ranges may be tuned through by selecting the correct values of such 10 fixed inductances. The variable capacities, or condensers, must stand long mechanical use and cause imperceptible electrical noise when operated in sensitive receiving sets. The tuning ratio of these variable condenser systems now in common use is about 3 to 1. The frequencies of 19,000 15 to 535 kc. covered by a so-called all-wave set therefore requires four different frequency ranges, and hence four different values of fixed inductances per tuning circuit. The variation in wiring, tube, coil and minimum variable condenser capacities makes necessary the use of a 20 number of small trimming condensers to enable the necessary accurate alignment of the several tuning circuits in the manufacture of the all-wave receiving set. Before the present variable condenser tuning vogue, tuning was done by varying the inductance associated with a fixed capacity. The variable condenser method however became more economical and efficient than 25 the older inductance tuning method and lent itself better to the reasonably accurate "ganging" needed in modern multi-range and multi-stage circuits.

One object of the present invention is to provide 30 an improved inductance method of tuning which will possess all of the advantages of the prior variable condenser tuning types with reduced cost of manufacture. Another object is the reduction or elimination of trimmers. Another object is to increase the tuning ratio, thereby 35 reducing the number of tuning ranges required for the wide frequency coverage and resulting in operating simplicity. Another object is to broaden or narrow one or more predetermined frequency ranges. Another object is the 40 elimination of one or more ranges with resulting elimination of manual switching in the so-called "skip-band" sets. Other objects and advantages will be understood from the following 45 description and accompanying drawings which illustrate preferred embodiments of the invention.

Fig. 1 is a side elevation of the tuning control;

Fig. 2 is an enlarged bottom view of the slideable tuning carriage;

Fig. 3 is an end view thereof;

Fig. 4 is a side view thereof;

Fig. 5 is a diagram of connections of a receiving set embodying the invention;

Fig. 6 is a side elevation of a modified form of 5 tuning control; and

Fig. 7 is an end view thereof.

Referring to Fig. 1, a two-unit variable inductance embodying certain features of this invention is shown. These units are alike and mechanically coupled together by the Bakelite shaft 1 which is supported in the ball-bearing assemblies indicated by the blocks 2, 2 and rotated by the wheel and knob 3. In place of the Bakelite shaft 15 shown, a metal shaft with insulating coupling 15 would suffice.

Each variable inductance unit consists of a bare wire solenoid winding 4 or 4a made rigid by winding in a shallow helical groove cut or formed on the outer surface of a Bakelite cylinder 5. 20 Each unit also possesses a grooved contactor wheel 18 that rides along under compression on the wire as a track. The wheel 18 is in continuous contact with winding 4 or 4a touching it at one contact point. Each contactor is mounted in a carriage 6 which is forced by the wheel and wire engagement to move along its fixed guide 7 whenever the coils are rotated. Rotation of the coils thus varies their effective lengths and hence 25 their inductances. The low potential or ground lead to each unit is connected to the guides 7 by lugs 8, 8. Connection to the other sides of the variable inductances is through slip-rings 9 and brushes 10 mounted on brush holders 11. 30

The Bakelite cylinders are hollow, open at one 35 end and closed and supported at the other by Bakelite tight fitting inserted disks 12, 12 turned down to a smaller diameter to form supports for the slip-rings 9, 9 to which the nearest ends of the windings 4 and 4a are connected. The inside diameter of the end disks 12 form a tight fit on shaft 1 and the cylinders 5 are fastened thereto by pins 13, 13. 40

The metal angular frame 14 supports the assembly, together with an upright 15 of Bakelite. 45 The right hand inductance unit has inserted inside it a non-rotating primary winding 16 on another hollow Bakelite cylinder 16a attached as shown to the support 15, the shaft 1 passing through its center. The coil 16 is in inductive relation to the variable inductance coil 4a. Each variable inductance may contain 50 turns, thus requiring 50 rotations of the wheel and knob 3 to go from maximum inductance to zero of the coils 4, 4a, or vice versa. The windings 50

may be one inch in diameter, three inches long, and may have an inductance each of 18.7 microhenrys. The winding pitch is not uniform throughout the length of the coils as indicated in Fig. 1, and there may be roughly eight-tenths of the inductance or 40 turns in two inches, and two-tenths or 10 turns in the remaining one inch of the total winding length. The block 17 contains a Geneva stop gear for mechanically preventing the system from turning beyond the end limits of the 50 turn coils.

The wheel and knob unit 3 is constructed as shown to enable slow tuning by applying the hand to the large wheel, or rapid tuning by spinning the shaft at the knob. The wheel is a casting and made heavy near its periphery for the purpose of developing momentum when the coils are spun. About four smart spins will carry the tuning through its entire length. In place of the spinning knob attached to the side of the large fine adjustment wheel of 3, a small handle may be mounted on a pin affixed to the side of wheel, the handle revolving on a one or two inch diameter and being free to rotate on its pin. The guides 7 are respectively supported at one end by the upright 15 and frame 14, as shown in Fig. 1.

Figs. 2 to 4 show the contactor 18 and the carriage mechanism 6. The guide 7 has its center line parallel to the axis of its coil 4 or 4a. The carriage is composed of a plate 19 having strips 19a secured to opposite sides of its upper face. These strips are grooved on their inner edges which face similar grooves in the edges of guide 7. Balls 20 are located between these grooves and retained in place by pins 27, permitting free movement of the carriage along the guide. A pair of studs 23 are secured to the plate 19 and extend downwardly therefrom and slidably carry on their lower portions a truck 21. This truck has a crosspiece uniting the ends which slide upon the studs 23 and is yieldably pressed downwardly by springs 24 encircling the studs between the truck and the plate 19. On the lower central face of the truck is secured by screw 26, a bearing bracket 25. This bracket is U-shaped with its sides extending downwardly to journal shaft 18a of the contact wheel 18. By loosening the screw 26, the bracket may be turned to such an angle as to give its best average position to permit the contact wheel 18 to readily travel along the winding 4 or 4a, regardless of the varying pitch of the winding. The screw 26 may then be tightened to hold the bracket in fixed position. The contact wheel 18 is formed with bosses 18b on its sides which have reduced shoulder end bearings against the inside of the sides of the bracket 25 which minimizes the friction and play of the parts. The shaft 18a has a driving fit with the contact wheel and extends beyond the sides of the bracket 25. The outer ends of the shaft are engaged by brushes 28, 28 which are fastened to the truck and bent to be under pressure against each end of the steel shaft 18a. This gives a bonded contact between the contact wheel 18 and the truck 21. Electrical connection between the truck and the carriage is insured, or bonded by the flexible lead 29. Electrical connection or bonding between the carriage and the guide 7 is insured by a leaf spring 30 attached to the upper face of the plate 19, as shown in Figs. 3 and 4.

This bonding is important when using an assembly of metal parts which are relatively movable for radio tuning purposes, especially if the shorter waves are to be tuned. This is necessary

to prevent noise while tuning, such noise being caused by poor or intermittent contact of the parts in or near the sensitive circuit of an amplifier. For securing the best results the contact wheel 18 should be made of sterling silver. The bearing bracket 25 may be made of brass. The brushes 28 should be of sterling silver and shaft 18a should be plated with rhodium. The leaf spring 30 should be made of sterling silver.

Fig. 5 shows the variable inductances connected to form resonant tuning circuits in a superheterodyne receiver. The bare wire rotatable coils or windings 4 and 4a have one end of each connected to its slip-ring 9 on which presses a brush 10 which forms the terminal for each unit, as diagrammatically indicated in Fig. 5. The guides 7 are grounded as indicated. The non-rotatable winding 16 is indicated in Fig. 5 and is inductively related to its associated variable inductance and is here used as an oscillator "tickler". The upper and lower portions of Fig. 5 respectively represent the radio frequency antenna tuner and the oscillator tuner. The parts are inter-connected by a five-pole double-throw switch and the different portions of this switch are segregated and the two positions of these switch parts are indicated by the roman numerals I and II. Thus for the two tuning ranges of the embodiment shown, the switch parts will be thrown to position I for operation over one range and will be thrown to position II for operation over the other range. In switch position II, the range of this particular example is 535 to 3540 kc.; and in position I, the tuning range is 3480 to 19,000 kc. In series with the coils 4 and 4a are the inductances 32 with the upper coil 4 and 33 and 34 with the lower coil 4a as determined by the switch position. These inductances may be about .20 microhenry. These auxiliary inductances permit the variable use of the entire 40 turns of the coils 4 and 4a.

A pentagrid tube 35 is indicated in Fig. 5 and may be of the type 6A7 or 2A7 now in common use. This tube performs the functions of oscillator and mixer in the input of superheterodynes. This tube is employed in the usual manner here except that the circuits have been adapted to the present invention. The tube 35 comprises the control grid 36, the screen grid 37, the plate 38, the filament 39 heated by a source of voltage such as the battery 31, the cathode 40, the oscillator grid 41 and the oscillator anode grid 42. The resistance 43 furnishes the minimum control grid bias; and the capacity 44 by-passes the resistance 43. The capacity 45 serves as a blocking condenser, preventing the passage of direct current but permitting the passage of radio frequency current to the control grid 36. The resistance 46 acts as a radio frequency choke and at the same time conveys through the usual connection, the desired automatic volume control bias to the control grid 36. The capacity 47 acts to block direct current from the oscillator grid 41; and the resistance 48 supplies the desired oscillator bias through the drop caused by the current therein. To the output plate 38 of the tube is attached the intermediate frequency tuned primary shown as capacity 50 and winding 51 of the first transformer of the usual intermediate frequency amplifier represented by the dotted line rectangle 52. The battery 55 is a source of voltage for the plate 38 and the screen grid 37 of the tube 35. The capacities 49, 49 are by-pass capacities. The dotted rectangle 53 encloses a duplex-diode-triode detector, audio am-

plifier and automatic volume control tube and its associated circuit. The tube 53a may be of the well-known type 75 and is shown in a commonly used circuit making a detailed description unnecessary. The parts enclosed by the rectangle 53 indicate the source of automatic volume control voltage which by way of wire 54 is applied through the resistor 46 to the control grid 36 of the tube 35. The capacity 56 conveys 10 audio or signal frequency to the usual additional amplifier and signalling indicating device. It will be understood that instead of using the tube 35, two tubes may be substituted therefor in the usual manner, one tube being the first detector 15 or mixer and the other tube the oscillator.

Referring to the antenna input circuit in the upper part of Fig. 5, when the double throw switch is in position II, the rotatable coil 4 which may be of 18.7 microhenrys, is in series with a part of the end inductance 32 and resonates with the fixed capacity 51 which may be of .00462 microfarad to tune the input circuit of the tube 35 through a range of 535 to 3540 kc., a ratio of 6.62. The inductance of the part of the end inductance 32 used on the range of switch position II, plus the effect of leads, may be .44 microhenry at 3540 kc. The incoming signal frequency from the antenna 158 passes through the capacity 14 and through the resonant trap composed of coil 30 62 and capacity 61 to the tuning circuit 4 composed of part of inductance 32 and capacity 51. The variation in pre-selector circuit tuning is caused by the rotation of the upper coil 4 which causes the grounded contactor 18 to travel along 35 the outside of the coil 4, as already described. The trap 61, 62 excludes interference from signals in the region of the frequency of the intermediate frequency amplifier 52 which for these particular constants is tuned to approximately 40 490 kc.

The oscillator tuning circuit is tuned in unison with the antenna tuning circuit just described but always at a frequency differing therefrom by an amount equal to the intermediate frequency. In switch position II, the oscillator is always on the higher frequency side of the antenna circuit tuner and hence covers a range of 45 1025 to 4030 kc. As the two variable inductances are alike, this difference in tuning range is accomplished by using a fixed capacity 58 which may be of .00285 microfarad and by adding the shunt fixed padding inductance 59 as shown. The oscillator tickler or feed-back coil for this range consists of the fixed inductance 16 and the 50 fixed inductance 60. The inductance 16 is in inductive relation with the coil 4a; and the inductance 60 is in inductive relation with both inductances 59 and 34, the direction of the tickler windings being such as to cause oscillation. Thus the tickler circuit is from the anode grid 42, through coil 76 which is inoperative on range II, through coil 16, through coil 60 and thence to the positive terminal of a by-passed 55 voltage supply as 75.

When the switch is changed to position I, the oscillator is arranged to operate on the lower frequency side of the antenna tuning circuit and at the necessary 490 kc. separation therefrom. When the oscillator operates on a frequency 60 below that of the antenna tuning circuit, better signal to image and signal to noise ratios appear to be obtainable on the shorter wave lengths. With the antenna range from 3480 to 19,000 kc., the required oscillator range is from 2990 to 18,510 kc., a ratio of 6.22. This oscillator range is covered 75

by the coil 4a in series with the end inductance 33 and with fixed capacity 63 which may be of .0001 microfarad. The tickler circuit for range I comprises coil 76 which is coupled to the end inductance 33 and also includes coil 16 which is 5 coupled to the variable inductance 4a, a large capacity 61 which may be of .005 microfarad serving to short circuit the effect of coil 60, although utilizing this coil as a conveyor of direct current voltage from the source 75. units of Fig. 1 wherein the rotatable coil is shaped like a truncated cone. The winding is put on in the same pattern as previously indicated, that is, it may have 10 turns in the first inch of winding at the right end and 40 turns in the remaining two inches of axial winding length. The form 68 on which the coil 14a is wound may be of Bakelite. The carriage 6 is the same as previously described and travels along the guide 7 which is parallel to the side of the cone and in the plane of the cone's axis instead of being parallel to the axis of the coil. The structure is otherwise the same as described with reference to Figs. 1 to 4; and a two coil unit would be a repetition of the coil and contactor carriage added to the left. One advantage of the conical shape is that it gives more frequency change to a turn at the low frequency end of travel than the cylindrical form, while the desirable high frequency end spread remains substantially like that obtained with the cylindrical form. Another advantage is that the primary or tickler coil on form 69 may be closer coupled to the variable coil 14a for a given degree of mechanical clearance thus tending to avert oscillator tickler circuit resonance at the high frequency end of the high frequency range disturbing the tracking there.

The inductance, with a cone having diameters of one inch and two inches at the ends, or an average diameter of 1.5 inches, is about doubled compared with the cylindrical form of Fig. 1, assuming the same winding length and number of turns in each case. Consequently the fixed capacities required for tuning for all-wave coverage over the two ranges, are smaller than required for the cylindrical form of Fig. 1 and hence the resonant circuits develop a desirably higher voltage. However, as it may be desired to reduce the number of turns for ease of tuning without materially changing the high frequency broad tuning characteristic of Fig. 1, the conical shape offers a winding design of approximately 19 microhenrys when wound with 30 turns over a total axial length of two inches, keeping the mean diameter of 1.5 inches and spacing the first 10 turns at the right over one inch and the balance at the rate of 20 turns per inch. The shorter length of this 30 turn unit is of practical importance. The circuit of Fig. 5 applies whether the variable inductances are conical or cylindrical in shape.

Figs. 6 and 7 show how the left-hand guide 1a may be attached to the upright 15 by means of a machined piece 73 which supports the guide 55 1a and which is in turn secured to the upright. It will be noted that the guide 7 in this modification extends beyond the support 15. This overlapping of the guides 7 and 1a saves about one inch in length of a two unit assembly and about 60 one and one-half inches in a three unit assembly. Overlapping of the guides in the cylindrical coil form of Fig. 1 may be accomplished by staggering the fixed positions of the guides at differing angles around the coil axes, but in such a modification it is important that the coil forms be pinned to the shaft so that the angle between the guide and the starting point of the winding is the same for each coil.

Figs. 6 and 7 illustrate an automatic switching arrangement at the top which is especially applicable to the so-called skip-band set covering two ranges, such as from 535 to 1500 kc. and from 6000 to 19,000 kc. For such a pair of ranges the variable inductance would have a value of about 75 65.2 microhenrys. Mounted upon the support 15

is a U-shaped frame 78 which straddles the guide 7 and also the carriage 6 when the latter is moved to the end of the guide. The support 78 supports a block 79 in fixed position which in turn supports a series of switch elements 80 to the rear ends of which the circuit connections may be made. The front portions of the switch elements are flexible and carry contacts adapted to engage each other for certain connections in normal position and to form another relationship of connections when operated by the carriage 6. For this purpose, the lower or one of the lower contact elements may carry a roller 72 extending into the path of a cam 71 carried upon the top of the carriage 6. The contact elements may be initially set to assume certain positions and some of them may have intervening insulating blocks 81 to prevent adjacent contacts from engaging each other and arranged to give the desired change of connections when passing from one range of control to another. In the particular case considered, the cam 71 will come in contact with and push up the roller 72 of the switch assembly at a point where the variable inductance has dropped to approximately eight microhenrys. This point is approximately 35% of the axial winding length from the right-hand end of the coil. The coil data may be as follows: Axial length 3.2 inches, left end diameter 2.5 inches, small end diameter 1 inch, and a total of 30 55 turns made of 9 turns at a pitch of .1 inch starting at the right-hand end and with a balance of 46 turns at a pitch of .05 inch. Two such coil units are required to tune the antenna and the oscillator of a superheterodyne circuit as shown 35 in Fig. 5. The switch 80 comprises four double-pole double-throw portions; two portions being side by side with two tiers such as shown in Fig. 6. The switch used on the accompanying tuning unit comprises two such portions, making six portions in all. Five of these are utilized like the five portions shown in Fig. 5 and the sixth portion may be used to shift the illumination from a long to a short wave calibrated scale.

The circuit arrangement and constants already described for range I of Fig. 5 apply also to this skip-band range 6000 to 19,000 kc., excepting the increased size of the variable inductance 4 to 65.2 microhenrys, the termination of tuning at 6000 instead of at 3480 kc. calling for no modification. For the 535 to 1500 kc. range, the previously described circuit of range II applies together with the constants given, except the increase in size of the variable inductance to 65.2 microhenrys, the decrease in capacity 57 to .00134 microfarad, 55 and alterations in the inductance 59 and capacity 58 in order to track the oscillator tuning over this range. The inductance 34 becomes unnecessary but as it is a part of an assembly including capacity 58 and inductances 59 and 60, it may be left in the circuit.

It is apparent that the switch device 80 and actuator 72 could be made smaller and that two or more such devices could be arranged to be actuated by the movement of the carriage at predetermined points and thus permit two or more ranges to be skipped instead of one as has been above described.

Instead of using a rotating trolley or contactor wheel 18, a sliding contact or shoe may be substituted. In the structure previously described a sliding contact may be obtained by bending the springs 28 inwardly to cause sufficient pressure against the ends of the shaft 18a to prevent rotation of the contactor wheel 18. The rotating con- 75

tactor wheel has the advantage of offering less friction when spinning the coil as above described by means of the knob 3 of Fig. 1, but the sliding contact has the advantage of being self-cleaning. 5 A rotating contactor wheel of silver alloy used in conjunction with a copper wire coil heavily plated with fine silver may give satisfactory results if the mechanism is kept free of dust by proper enclosure. When using a sliding contact, 10 unlike metals having a natural lubricating effect are desirable. Such a combination is a shoe of silver or gold, or certain alloys of either one, sliding on a rhodium plated wire. Rhodium is very hard and gives excellent wearing qualities and at 15 the same time it is practically unaffected by the atmosphere. In such a combination the shoe wears out first which makes it easy to service the set by merely replacing the shoe. The combination of two precious metals, the harder one plated 20 on the wire and the softer one forming the shoe, presents a very low sliding friction; and a sliding contact has the advantage of self-cleaning. The plating metal on the wire or coil must have a comparatively low electrical resistance in addition 25 to presenting a bright clean surface to the contactor shoe or contactor wheel. The slip-rings 9 and brushes 10 should be such as to add no appreciable electrical resistance to the circuit as they are in the resonant circuits and should also 30 have low friction to rotation. A rhodium plated brass slip-ring and a silver or gold alloy brush lightly lubricated is satisfactory and durable. The use of a contactor wheel as a non-rotating sliding shoe has the advantage of being readily 35 turned to a new position and thus affords a number of new contact surfaces.

As rhodium is too hard to be buffed, it is necessary to thoroughly clean, polish and buff the wire and the slip-ring before plating them with rhodium. 40 In case the wire or the slip-ring be made of copper or brass, the base metal is cleaned, buffed, polished and nickel plated before being plated with rhodium. This process results in a bright, hard, smooth rhodium surface. Lubrication 45 when used should be light and a tight enclosure is desirable to avoid any accumulation of dust.

Where an amplifier vacuum tube is placed in circuit between two of the variable inductance 50 tuning units, electrostatic shielding is necessary to prevent undesired oscillations as in any system. Such shielding will also prevent undesired pick-up. When using one of these tuning units in the plate circuit of a vacuum tube for radio frequency 55 amplification, the coupling from the plate to the resonant circuit may be accomplished by the non-rotating coil 16, but as there is considerable clearance between the coil 16 and 4 in Fig. 1, higher impedance is obtained when the resonant 60 circuit is connected directly across the tube output.

Under certain circumstances, as where larger variable inductances are used especially if shielded, it is necessary to ground the unused part of 65 the variable coils, in which modification it is desirable to insert a small fixed inductance 82, as shown in Fig. 5 in series with the added ground connection to prevent end turn short-circuiting when the contactor approaches the low frequency 70 end of travel. Such added ground connection is made through an additional slip-ring 83 and brush 84.

It is to be understood that the scope of my 75 invention is not to be limited to the particular disclosures made. For instance, the coil instead

of rotating against a guided contactor could be made stationary and the contactor mounted on a carriage revolving around the inside or outside of the coil. The side of the coil, instead of being a straight line, might be in the form of an arc of a circle with the contactor carriage mounted at the end of a radial arm the other end of which would be able to turn in a pivot located at the center of the circle. It is also obvious that a variable condenser might be mechanically attached 10 to one of the variable inductance units to vary the capacity of a resonant circuit at the same time the inductance is varied. High frequency iron such as that known commercially as ferro-cart may be inserted in the coils to increase their 15 inductance, permitting the use of a smaller fixed capacity on the low frequency range and thus desirably increase the resonant circuit gain. Also this invention applies equally well to transmitters as to receivers if the necessary insulating and 20 current carrying requirements are met. It is also obvious that any type of frequency indicating scale may be attached or geared to the carriage or rotating system.

Various other modifications and applications 25 of the invention may be made without departing from the scope thereof.

I claim:

1. A variable inductance device comprising a pair of spaced upright supports, a rotatable shaft 30 extending therebetween and pivoted therein, a hollow coil form surrounding said shaft with its axis concentric with said shaft, said form being rigidly secured to said shaft at one of the form ends, the other end of said form being open and 35 free of support, a bare conductor helically wound on said form and a contactor member guided along the side of said form parallel to said side and arranged to make continuous sliding contact with said helical conductor when the shaft, form 40 and helix are rotated, a second coil form surrounding said shaft and rigidly supported in cantilever fashion on the one of said upright supports at the unsupported open end of said first form and projecting inside said first form, and a 45 coil winding on said second form.

2. A variable inductance device comprising a pair of spaced upright supports, a rotatable shaft extending therebetween and pivoted therein, a hollow cylindrical coil form surrounding said 50 shaft with its axis concentric with said shaft, said form being rigidly secured to said shaft at one of the form ends, the other end of said form being open and free of support, a bare conductor helically wound on said form and a contactor 55 member guided along the side of said form parallel to said side and arranged to make continuous sliding contact with said helical conductor when the shaft, form and helix are rotated, a second coil form surrounding said shaft and rigidly supported in cantilever fashion on the one of said 60 upright supports at the unsupported open end of said first form and projecting inside said first form, and a coil winding on said second form.

3. A variable inductance device comprising a 65 pair of spaced upright supports, a rotatable shaft extending therebetween and pivoted therein, a hollow conical coil form surrounding said shaft with its axis concentric with said shaft, said form being rigidly secured to said shaft at one of the 70 form ends, the other end of said form being open and free of support, a bare conductor helically wound on said form and a contactor member guided along the side of said form parallel to said side and arranged to make continuous sliding 75

contact with said helical conductor when the shaft, form and helix are rotated, a second coil form surrounding said shaft and rigidly supported in cantilever fashion on the one of said upright supports at the unsupported open end of said first form and projecting inside said first form, and a coil winding on said second form.

4. A variable inductance device comprising a bare conductor formed into a helix and means supporting said helix for rotation about its axis a guide bar supported along the side of said helix, a contact member guided by the conductor of said helix and also guided by said guide bar whereby said contact member will travel along the conductor of said helix when said helix is rotated and will be driven by said helix along said guide bar, and an electric switch having actuating means positioned in the path of travel of said contact member along said guide bar so as to be actuated by said contact member at a predetermined position in its travel along said bar.

5. A variable inductance device wherein a coil

formed of a bare conductor is supported for rotation about the coil axis, a guide bar individual to said coil is supported in spaced parallel relation to the side of the coil and a contactor engages both the guide bar and the coil and travels along the guide bar and the conductor of the coil whenever the coil is rotated to vary the inductance of the device, characterized by the fact that said contactor is positioned between said guide bar and said coil and comprises a carriage movable along said bar in contact therewith and a truck having a trolley wheel pinioned therein, said wheel being grooved to the conductor of said coil so as to travel along said conductor as a track when said coil is rotated, and spring means in compression between said truck and said carriage urging said truck away from said bar and toward said coil so as to hold said trolley wheel on said wire and electric conductive means providing an electric conductive circuit between said guide bar and coil conductor.

PAUL WARE.
